UNITED STATES PATENT OFFICE

GEORGE M. HINELINE, OF RICE LAKE, WISCONSIN

ROTARY SNOW REMOVER

Application filed August 28, 1928. Serial No. 302,559.

This invention relates to new and useful improvements in snow plows and has for its prime object to provide a simple and efficient means for removing snow from a road or highway, and means associated therewith for discharging the snow removed from the road to the outside of the highway proper, thereby eliminating the process of ridging the snow along the track at each side of the highway, and thus leaving the highway clear and clean for another snow.

Another very important object of the invention resides in the provision of a snow plow of the above mentioned character which is of such a construction as to enable the same to be readily attached to any standard makes of tractor and to be driven by said tractor.

A further very important object of the invention resides in the provision of a snow remover of the above mentioned character which is thoroughly reliable in operation, strong and durable, inexpensive to manufacture, compact and convenient in its arrangement of parts, easy to manipulate, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

35 In the drawings:

Figure 1 is a top plan view of the snow remover, embodying the features of my invention.

Figure 2 is a side elevation thereof.

40 Figure 3 is a transverse vertical view, taken through the floor and discharge spout portion of the remover.

Figure 4 is a vertical longitudinal section through the snow remover.

45 Figure 5 is a detail transverse section taken

substantially on the line 5—5 of Figure 4.

Figure 6 is a transverse section through the spout.

Figure 7 is a perspective view of an attachment bar, and

Figure 8 is an enlarged detail elevation of the outer end of the discharge spout.

Referring to the drawings in detail, it will be seen that numeral 5 denotes the two channel bars which are disposed in spaced co-extensive relationship, being attached to extension frame chassis bars 6 of a tractor 7, by means of elongated plates 8, bolted thereto as at 9. These frame bars 5 have their forward ends inclined downwardly and forwardly. A scoop S is mounted on the forward portion of the bars 5 and includes a bottom 10, having a downwardly bowed rear central portion 11, merging into the bottom portion of a frusto-conical trough like flange 12, which merges at its smaller rear end into a cylindrical fan casing 14, that is supported between the bars 5, by a cradle bar or structure 15, which has its ends fastened in the channels of the bar 5 as shown at 5'. This fan casing 14 is braced, as at 15', in respect to an upright inverted U-shaped frame 16, rising from the rear portions of the bars 5 and rigidly attached thereto. This upright frame member 16 is braced in respect to the radiator of the tractor 7 as at 18. A centrifugal fan-like structure is mounted in the casing 14 and includes a plurality of blades 19, radiating from a shaft 20, journaled in a bearing 21 in the center rear wall of the casing. This fan has a conical shaped deflector 23, coaxially mounted thereon in respect to the fan. A tangential outlet 24 projects from the lower portion of the casing to one side and has hingedly connected thereto, as at 25, a discharge spout 26, of cylindrical construction. Opposite the hinge is a flexible covering 27 of spherical segmental configuration between the outlet 24 and the spout 26. At the upper end of the spout 26 there is hingedly mount-

ed as at 28, a plurality of sections 29, for directing the snow being discharged at the desired height.

5 A bracket 30 rises from the top of the casing 14, and support brackets 31 and 32 with pulleys 33 and 34 respectively therein. A cable 35 is trained over the pulley 33 and connected to the end section 29 so that the sections may be collapsed or extended, these 10 sections being normally extended by springs 36. A cable 37 is trained over the pulleys 34 and attached to an intermediate portion of the spout 26, as at 38, so that the spout may be raised and lowered as desired.

15 It is thought that the construction, operation, utility and advantages of this invention will now be quite apparent to those skilled in this art, without a more detailed description thereof. It will be apparent that 20 changes in the details of construction, and in the combination and arrangement of parts may be resorted to, without departing from the spirit or scope of the invention as herein-after claimed or sacrificing any of its advantages 25 and thereby the present embodiment of the invention has been disclosed in detail merely for the purposes of exemplification, because in actual practice it attains the features of advantage enumerated as desirable 30 in the statement of the invention and the above description.

Having thus described my invention, what I claim as new is:

1. In a snow plow construction, a scoop, 35 a fan casing having an outlet therein, a fan in the casing, a deflecting flange joining the scoop and fan casing, a pair of spaced bars connected at their forward ends to the scoop and at their rear ends, adapted to be connected to a vehicle chassis frame, a cradle bar joined at the opposite ends to said bar, an intermediate portion of said cradle bar arranged in underlying abutment to the fan casing for supporting the latter, said spaced 40 bars formed with inwardly directed channels, the ends of the cradle bar being anchored to said channels, an upright inverted U-shaped frame disposed rearwardly of the fan casing and having the ends thereof anchored to the spaced bars, and straps secured to the U-shaped frame and the fan casing for supporting the fan casing.

2. In a snow plow construction, a forwardly directed scoop, a circular fan casing, a fan in said casing, said fan casing having an outlet, a rearwardly and inwardly directed deflector flange beneath the rear portion of the scoop and the forward portion of the casing, a pair of forwardly projecting 50 spaced co-extensive channel bars adapted to be connected to the chassis frame of a vehicle at their rear ends and at their forward ends to the scoop, a cradle bar having its opposite ends in the channels of said bars and 55 having an intermediate portion of said

cradle bar in abutment with the under side of the fan casing for supporting the latter, an inverted U-shaped upright frame secured at its lower edge to said bars, and a pair of straps secured to and projecting forwardly from the legs of the U-shaped frame and said straps secured at their outer ends to said fan casing for supporting said fan casing.

In testimony whereof I affix my signature. 75
GEORGE M. HINELINE.
